US00D995330S

(12) **United States Design Patent** (10) Patent No.: **US D995,330 S**
Matsumoto et al. (45) Date of Patent: **** Aug. 15, 2023**

(54) **WEARABLE DEVICE WITH A BAND**

(71) Applicant: **Amazon Technologies, Inc.**, Seattle, WA (US)

(72) Inventors: **Ippei Matsumoto**, Daly City, CA (US); **Bernhard Wildner**, San Francisco, CA (US)

(73) Assignee: **Amazon Technologies, Inc.**, Seattle, WA (US)

(**) Term: **15 Years**

(21) Appl. No.: **29/834,619**

(22) Filed: **Apr. 13, 2022**

Related U.S. Application Data

(62) Division of application No. 29/702,420, filed on Aug. 19, 2019, now Pat. No. Des. 949,720.

(57) **CLAIM**

The ornamental design for a wearable device with a band, as shown and described.

DESCRIPTION

FIG. 1 is a front, left perspective view of a wearable device with a band;

FIG. 2 is a back, left perspective view thereof;

FIG. 3 is a right-side view thereof;

FIG. 4 is a left-side view thereof;

FIG. 5 is a top view thereof;

FIG. 6 is a bottom view thereof;

FIG. 7 is a front view thereof; and,

FIG. 8 is a back view thereof.

The dashed broken lines depict portions of the wearable device with the band that form no part of the claimed design. The dot-dashed broken lines represent boundaries of the claimed wearable device with the band and form no part of the claimed design.

1 Claim, 8 Drawing Sheets
